UNITED STATES PATENT OFFICE.

HERMAN G. PAPE, OF NEW YORK, N. Y., ASSIGNEE TO RALPH A. SCHOENBERG, NOW BY
JUDICIAL CHANGE OF NAME, RALPH A. BELMONT, OF NEW YORK, N. Y.

DUPLEX SWITCH.

1,268,485. Specification of Letters Patent. Patented June 4, 1918.

Application filed July 8, 1917. Serial No. 178,486.

To all whom it may concern:

Be it known that I, HERMAN G. PAPE, of New York city, in the county and State of New York, have invented a new and useful 5 Duplex Switch, of which the following is a specification.

It is very desirable at times to install two switches in place of one and this has necessitated the injuring of walls for the insertion 10 of a new outlet box but with my invention I can use a plurality of narrow switches and insert them in an ordinary outlet box because of my saving of space.

A feature of my invention consists in 15 using a portion of one switch box or housing as a closure for the adjacent box or housing, and in the preferred form I provide a rectangular switch box having three sides and a bottom, the ordinary box having four sides 20 and a bottom, and one of the sides of one of my boxes is used to cover the open side of another of my boxes, my boxes being arranged side by side and as an example I show two although more might be used, and 25 in making my boxes in this way it will be clear that there is a great saving in material and the box which is preferably of porcelain will be cast much more accurately because of its being more open in the casting.

30 Another feature of my invention consists in using a right-angled extension of the attachment plate as a closure for the open side of the box at one end of the series.

Another feature consists in placing the 35 binding posts on those sides of the box which are exposed when the plurality of switches are assembled and preferably near the bottom for ready wiring.

Another feature consists in making the attachment or guide member cover the entire 40 top of the switch housing and in the preferred form covering the tops of the plurality of housings so as to cover and protect the mechanism in case, for example, the face plates are not applied until the building is 45 finished.

A feature of my invention is the compactness of the switch mechanism itself and if desired it might be made even more compact 50 by using instead of the spring I show, a coiled spring bent over as in Fig. 3 of my Patent No. 1190451 dated July 11, 1916.

Other features will be pointed out below.

In the drawings,

55 Figure 1 is a central longitudinal sectional

view of a duplex switch embodying my invention:

Fig. 2 is a section on line 2—2 of Fig. 1;
Fig. 3 is a plan of the actuating member;
Fig. 4 is a plan of the contact member; 60
Fig. 5 is an end view on a reduced scale
of the switch shown in Figs. 1 and 2, and
Fig. 6 is a modification described below.

My switch comprises a hollow body 1 of insulating material fastened by screws 2, 2, 65 to a side plate 3 integral with and projecting perpendicularly from, an attachment and guiding plate 4 by means of which the switch is fastened in place upon the usual junction box (not shown). Within the body 70 1 is secured the switch mechanism which includes a base plate 41 fastened by two screws 5 and 6 to body 1 and formed with an aperture to receive the end of a stud screw 8 by means of which an actuating member 9 is 75 pivotally secured thereon. Upon the lower portion 10 of base plate 41 is seated the movable contact member 11 pivotally connected with said plate by a stud 12 projecting from the latter. This stud 12 has one end riveted 80 to base plate 41 and the contact member 11 is held in position between the base plate 41 and actuating member 9.

Push buttons 13 and 14 are pivotally connected to the actuating member 9 and fit in 85 recesses 15 and 16 respectively, the inner walls of the recesses limiting the movements of the push buttons and consequently of member 9.

A bow spring 17 connects the two members 9 and 11 and serves as a means through which the oscillating movements of member 9 act to oscillate the driven member 11. One end 17^a of this bow spring 17 is bent laterally between the members 9 and 11 and has 90 its extremity again bent perpendicularly and swiveled in a round hole provided in actuating member 9. The other end 17^b of bow spring 17 is straight and extends through a clearance hole 19 in member 9 into and 100 through a round hole formed through movable contact member 11 parallel with the hole of member 9 for end 17^a and within which it is swiveled. This straight end of spring 17 projects beyond member 11 into 105 an arcuate slot 21, whose ends serve as stops or abutments which limit the movements of member 11 in both directions.

When the outer push button is pressed inwardly the hole within which the end 17^b 110

of spring 17 is swiveled is moved around the axis of stud screw 8 toward the hole within which the opposite end 17^b of spring 17 is swiveled, thereby increasing the stress of 5 said spring and also changing the direction of the application of its force to member 11. When the direction of the application of the force of spring 17 to member 11 has been changed to such an angle with relation to 10 stud 12 that said force starts to swing member 11 on stud 12, then said member is snapped in one quick movement to the opposite extreme of its movement. Thus there is no creeping movement of member 11 at 15 the start but its movement is a quick and snappy one throughout. The reason for this is due mainly to the fact that the movement of member 11 itself supplements the movement of member 9 in the effect of the latter 20 upon the direction of the application of the force of spring 17 upon member 11. Of course when the parts are at rest the spring 17 which is normally under stress holds both the actuating and actuated members each at 25 the limit of its movement in either direction.

The contact member 11 is made with two resilient contact arms 22 and 23 the former being radially shorter than the latter and 30 passing by stationary contact 24 but making contact with stationary contact 25 while movable contact arm 23 makes contact with stationary contact 24 the angular movement of member 11 being greater than the angular distance apart of the stationary contacts.

The stationary contacts are held in place by screws 26 and 27 which pass through the body and hold in place plates 28 and 29 40 which carry, and form extensions of, binding posts 30 and 31 for lead wires.

Each body 1 has a bottom 1^a and three sides 1^b, 1^c and 1^d, one side and the top being open, so that I dispense with one side wall 45 for each body using the side wall 1^d as a closure for the open side of the adjacent body, the open side of the upper body in Fig. 2 being closed by side plate 3. It will be observed in Fig. 2 that screws 2, 2, hold 50 both boxes to the side plate 3 so that the boxes are attached to attachment plate 4 while the extension or projecting plate 3 covers the open side of the upper box shown in Fig. 2.

55 It will be clear that the binding posts 30 and 31 are on the sides of the boxes which are exposed when the boxes are assembled so that they are readily accessible for wiring and they are preferably near the bottoms of 60 the bodies or boxes so as to be near the holes in outlet boxes.

The plates 28 and 29 pass between adjacent boxes, each box being grooved for its plates, and the grooves being covered by the 65 adjacent box or body.

In Fig. 6 I show four switches with two face plates illustrating that I provide four switches in the space heretofore occupied by two switches, this result being in part due to the construction of the boxes and in part to 70 the thinness of the switch mechanism, it being clear that the base plate 41, members 9 and 11 and the stationary contacts are all alined in substantially the same plane.

It will be clear that although I show two 75 switches I may use any desired number side by side, the side wall 1^d of each box serving as a closure for the open side of the adjacent box, the side plate 3 serving as a closure for the open side of the end box of the series. 80

What I claim is:

1. In an electric switch in combination an oscillating contact member provided with two contact arms of different lengths and two stationary contacts with which said oscillating contact members coöperate, said stationary contact members being located at different distances from the pivot of said oscillating member corresponding in position each with the length of one of said arms 90 so as to be engaged only by said one arm, the angular movement of the oscillating member being not less than the angular distance apart of the stationary contacts; and means for actuating said oscillating member, said 95 actuating means, said oscillating member and said fixed contacts being all alined in substantially the same plane.

2. In an electric switch in combination an oscillating contact member provided with two contact arms of different length; and two stationary contacts with which said oscillating contact members coöperate, said stationary contact members being located at different distances from the pivot of said oscillating member corresponding in position each with the length of one of said arms so as to be engaged only by said one arm; means to hold said stationary contacts at a certain angular distance apart with reference to said pivot; and means including a spring to give the oscillating member in each direction of its oscillation angular movement not less than the angular distance apart of the stationary contacts. 110

3. An electric switch comprising an actuating member; a contact-carrying member; a bow spring having a hooked connection with one of said members and an operative connection with the other of said members, said spring being twisted on its axis by the actuating member and when twisted actuating the contact-carrying member; and a fixed contact coöperating with the contact-carrying member. 120

4. An electric switch comprising an actuating member; a contact-carrying member; a bow spring having one or more coils and having a hooked connection with one of said members and an operative connection 130

with the other of said members, said spring being twisted on its axis by the actuating member and when twisted actuating the contact-carrying member; and a fixed contact 5 coöperating with the contact-carrying member.

5. An electric switch comprising push buttons; an actuating oscillating member operated by the push buttons; an oscillating 10 contact member; a bow spring having a

hooked connection with one of said members, said spring being compressed and twisted or turned on its axis by the actuating member and when so twisted or turned actuating the contact member, said spring 15 moving bodily into reverse position; and a fixed contact coöperating with said contact member.

HERMAN G. PAPE.
